UNITED STATES PATENT OFFICE.

LOUIS WINTHROP BARTA, OF WINCHESTER, MASSACHUSETTS.

FOLDING CARTON.

1,202,648.

Specification of Letters Patent. Patented Oct. 24, 1916.

Application filed March 13, 1916. Serial No. 83,796.

To all whom it may concern:

Be it known that I, LOUIS WINTHROP BARTA, a citizen of the United States, residing at Winchester, in the county of Middlesex and State of Massachusetts, have invented new and useful Improvements in Folding Cartons, of which the following is a specification.

The object of the present invention is to provide an improved folding carton adapted to be used for transporting and displaying articles of food, such for example as crackers and cereals.

Of the accompanying drawings, which illustrate one form in which the invention may be embodied: Figure 1 represents a face view of a blank suitably cut and scored and adapted to be folded to provide the carton hereinafter described. Fig. 2 represents a perspective view of the same blank, some portions of which are folded to operative position and other portions of which are in intermediate positions of folding. Fig. 3 represents a perspective view similar to Fig. 2 but showing the blank as having been completely folded with the exception of the outer lid portion. Fig. 4 represents a sectional view in a transverse vertical plane intersecting the upper left-hand portion of the carton in its condition of use. Fig. 5 represents a perspective view of a sliding shutter adapted to be used in conjunction with the carton to display the contents of the latter. Fig. 6 represents a perspective view of a packing shutter adapted to be used in conjunction with the carton until it is desired to display the contents.

The same reference characters indicate the same parts wherever they occur.

The blank as shown by the drawings may be made of a single piece of sheet material such as cardboard, or any other relatively inexpensive material. As shown by Fig. 1, the blank comprises a lid portion 10, a back portion 11, a bottom portion 12, a front portion 13, and another lid portion 14, all arranged in series and adjoining each other in the order named. The junction between the portions 10 and 11 is defined by a line of scoring *a*, that between portions 11 and 12 by a line of scoring *b*, that between the portions 12 and 13 by a line of scoring *c*, and that between portions 13 and 14 by a line of scoring *d*. *a--b* is greater than *c--d*.

Lid portion 10 has locking flaps 15, 15 adjoining its opposite side marginal por-

tions defined by lines of scoring *e*, *e*. Each flap 15 has locking tabs 16, 16 adapted to enter slits 17, 17.

Back portion 11 has confining flaps 18, 18 adjoining its opposite side marginal portions defined by lines of scoring *f*, *f*; bottom portion 12 has lid-supporting flaps 19, 19 adjoining its opposite side marginal portions defined by lines of scoring *g*, *g*. When the blank is folded into the form of a carton, back portion 11, front portion 13 and flaps 19, 19 are the four upstanding walls against which the contents of the carton are to be packed.

Front portion 13 has confining flaps 20, 20 adjoining its opposite side marginal portions defined by lines of scoring *h*, *h*. These flaps are provided with locking tabs 21 adapted to enter slits 22 in flaps 18, as shown by Fig. 3. Fig. 2 shows the back portion 11, flaps 19, 19, and flaps 18, 18 as having been bent up to operative position, and shows the front portion 13 as having been bent part way toward operative position, and locking tabs 21 about to enter slits 22. Flaps 18, 18 and 20, 20, become interlocked with each other by the coaction of tabs 21 and slits 22, and the upright walls of the structure are thereby confined to hold the structure intact. The lid-supporting flaps 19, 19, however, are folded on lines *g*, *g* before the flaps 18 and 20 are folded toward each other, and are confined within the enclosure by the confining flaps, thus providing two double walls. Lid portion 14 has flaps 23, 23 adjoining its opposite side marginal portions defined by lines of scoring *j*, *j*.

The length of each flap 19 from score line *g* to edge *k* is the same as length *c--d* of front portion 13. Consequently, when lid portion 14 is folded downwardly on score line *d* with flaps 23 overlapping flaps 19, lid portion 14 rests upon edges *k*, *k* and is supported by flaps 19. Flaps 23, 23, however, do not enter the packing space, but each lies between an inner wall 19 and an outer wall 18, 20, as shown by Fig. 4. Consequently, if the contents of the carton be soda crackers or any other article of a fragile nature, they will not be chipped, cracked, or otherwise injured by folding the lid portion 14 to the position shown by Figs. 3 and 4. In this respect flaps 19 serve as guards to protect the contents when the packer is closing the lids of the carton after having packed the latter. When the confining flaps 18 and

20 are interlocked with each other as shown by Fig. 3, the slits 17, 17 are in position to receive the locking tabs 16, 16 formed upon the flaps of the lid portion 10. As lid portion 10 is folded down from the position shown by Fig. 3, the two lower tabs 16 may be tucked into the slits 17 in flaps 18, and finally the two upper tabs 16 reach positions in register with the slits 17 of flaps 20, and 10 may be tucked into the latter.

The two lid portions 10 and 14 have hand-holes 10' and 14'. These hand-holes register with each other when the two lid portions are folded to closed positions, and 15 afford access to the contents of the carton so that said contents may be removed without opening either of the lids.

Fig. 5 shows a display shutter intended for use by a retail dealer, and Fig. 6 shows 20 an opaque shutter intended to be applied by the packer to cover the hand holes until the carton is opened by the retail dealer. The display shutter (Fig. 5) comprises a frame 24, and a panel 25 of transparent material 25 such as glass or celluloid. The packing shutter (Fig. 6) consists of a sheet 26 of inexpensive material such as cardboard. One or more shutters 26 may be placed on top of lid 10, or may be placed between lids 10 30 and 14, when the carton is wrapped. Assuming that the carton had been packed and lid portion 14 folded to closed position as shown by Fig. 3, the next step would be to fold down lid portion 10 and insert tabs 16 35 into the slits 17. The carton could then be inclosed in a sheet of thin wrapping paper, indicated conventionally by dotted line A in Fig. 4, pasted upon it to seal lid portion 10 and to seal also the cracks and slits through 40 which dust and moisture might otherwise enter.

Edges *m* of flaps 18 and edges *o* of flaps 20 occupy a higher plane than edges *k* of flaps 19 when all the said flaps are in operative position. This relation of the edges is shown by Fig. 4 and is also shown by Fig. 2 so far as edges *m* and *k* are concerned. Consequently, when lid portion 10 is folded down over the lid portion 14 as shown by 50 Fig. 4, lid portion 10 will be supported by edges *m* and *o* above and independently of the shutter that may be resting upon lid portion 14. Lid portion 14 being thus supported in one plane by flaps 19, 19, and lid portion 10 being thus supported in a higher 55 plane by flaps 18 and 20, insures a suitable space between the two lid portions for the sliding shutter to be moved edgewise without being pinched or otherwise cramped between 60 the two lid portions.

Assuming that the packed cartons are sealed in wrapping paper pasted thereon as hereinbefore mentioned, and that each carton is provided with an opaque shutter 26, 65 the retail dealer having a stock of display

shutters such as that shown by Fig. 5 would prepare a carton for display as follows:— The sealing wrapper could be cut or scored with a knife around the outline of lid portion 10, and the cut piece could be removed. 70 The packer's shutter 26 could then be removed and the display shutter shown by Fig. 5 could be inserted between the lids 10 and 14 as shown by Fig. 4. The panel 25 of transparent material in the display 75 shutter is substantially the same shape and size as the hand holes 10' and 14' and would afford a view of the contents of the carton. It would not be necessary to detach the display shutter from the carton in order to 80 reach into the latter through the hand-holes, but the display shutter could be left projecting forwardly with its rear marginal portion between the lid portions 10 and 14. Even though all but an inch, more or less, of 85 the display shutter might be withdrawn from between the lid portions, the shutter would nevertheless be amply supported because the lid portion 10 is firmly locked by tabs 16 and would not be pried upwardly 90 by the weight of the outstanding portion of the shutter.

It is intended that the retail dealer will keep the display shutters but will throw each carton into the waste as it is emptied, 95 the cost of the cartons being less than the cost of returning them to the packer in suitable condition for second use.

I claim:

1. A carton consisting of a folding blank 100 and comprising a rectangular bottom, six upstanding walls, and two lids, four of said walls being arranged to form a rectangular inclosure and the two others being arranged in contiguous relation to the inner faces of 105 two opposite walls of said four walls, whereby such inclosure is provided with two opposed double walls and two opposed single walls, the upper edges of the outer members of said double walls being higher than the 110 upper edges of the inner members thereof, said lids adjoining the upper edges of said two single walls respectively, one of said lids being arranged to rest upon said upper edges of said inner members and having 115 flaps between said inner members and said outer members, and the other one of said lids being arranged to rest upon said upper edges of said outer members and having flaps lying against the outer faces of said 120 outer members, said lids having holes in registration with each other.

2. A folding blank adapted to form a carton, and comprising five wall-forming sections arranged in a series, wall-forming flaps, 125 adjoining the side marginal portions of the second, third and fourth of said sections, and retaining flaps adjoining the side marginal portions of the first and fifth said sections, said first and fifth sections being 130

adapted to fold, one over the other, to form a double lid, and having hand holes adapted to register with each other, said blank having parallel lines of scoring defining said 5 five sections, one from another, and lines of scoring defining said flaps from said sections, one of said sections that adjoin said third section being shorter than the other, said wall-forming flaps that adjoin said 10 third section being of the same length as said shorter section to sustain the lid section that adjoins the latter, said flaps that adjoin said second and fourth sections having coöperative tabs and slits adapted to be 15 interlocked to sustain said second and fourth

sections in parallel confronting relation, and to sustain said flaps of said third section in parallel confronting relation, two or more of said interlocking flaps having edges arranged to sustain the outer lid section apart 20 from the inner lid section to provide a space between said lid sections, said flaps that adjoin the outer lid section, and two or more of said interlocking flaps, having coöperative tabs and slits adapted to be interlocked 25 with each other to hold said outer lid section in closed position.

In testimony whereof I have affixed my signature.

LOUIS WINTHROP BARTA.
